Inventor
Charles C. Gates.

By Attorney

UNITED STATES PATENT OFFICE.

CHARLES C. GATES, OF DENVER, COLORADO.

DRINK-DISPENSING APPARATUS.

1,359,050.

Specification of Letters Patent. Patented Nov. 16, 1920.

Application filed June 28, 1919. Serial No. 307,419.

To all whom it may concern:

Be it known that I, CHARLES C. GATES, a citizen of the United States, residing at the city and county of Denver and State of Colorado, have invented certain new and useful Improvements in Drink-Dispensing Apparatus; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in drink-dispensing apparatus and, to be more specific, comprises a rotary head operated by an electric motor, the construction being mounted in a casing, and open at the end adjacent the head to permit the introduction of the hand of the operator in order to place the fruit, as half an orange, into contact with the rotary head, which is also longitudinally slideable on its shaft, whereby a valve is operated to allow liquid to be brought into contact with the head, and the fruit, all of which passes through an outlet into a glass or other receptacle. Furthermore, the valve operated by the head as aforesaid, is located in a casing which communicates with a number of pipes, each of which is in communication with a source of liquid under pressure, whereby the liquid which is dispensed at each operation of the head may be taken from any one of the pipes, as desired, by simply pressing a button which controls the passage of liquid through each pipe, the construction being such that the movement of the push button in the first instance closes the motor circuit, but by further pressure the valve controlling the passage of liquid through the desired tube is opened.

Having briefly outlined my improvement, I will proceed to describe the same in detail, reference being made to the accompanying drawing, in which is illustrated an embodiment thereof. In this drawing:

Figure 1 is a vertical section taken through my improved drink-dispensing apparatus.

Fig. 2 is a detail view of the mechanism for closing the electrical circuit and opening the valve of any one of a plurality of pipes.

Fig. 3 is a top plan view of the apparatus with the upper half of the casing or housing removed.

Fig. 4 is an end elevation of the structure, being a view looking in the direction of arrow 4, Fig. 3.

The same reference characters indicate the same parts in all the views.

Let the numeral 5 designate a housing which, as shown in the drawing, is composed of a lower member 6, and an upper member 7. The lower member has a horizontal partition 8, upon which rests an electric motor 9, whose shaft 10 is provided with a sleeve 12 at its outer extremity, this sleeve being fast on the shaft. Splined upon the sleeve between its inner end and a forward shoulder 13, and slideable on the sleeve is an oval head 14 which is provided with openings of any desired shape. As shown in the drawing there are elongated openings 15 located in the rear of the small end of the head, the latter being perforated as shown at 16. These openings allow the pulp and juices of the fruit to pass into and out of the head. Connected with a hub 17, with which the head is provided, is an arm 18, which engages a circumferential groove formed in the hub, thus permitting the head to rotate freely, independently of the arm. However, as pressure is applied to the head, as the fruit is held in contact therewith, the head 14 and arm 18 are moved rearwardly, or toward the left, referring to Figs. 1 and 3, whereby a longitudinally movable stem 19 controlled by a spring 119 is actuated to open a valve 120, the latter being located in a casing 21, which is in communication with a number of pipes 22, 23 and 24, each of which is in communication with a valve casing 123, normally closed by a valve 120, which cuts off the chamber of the casing 123 from a chamber 25, which is in communication with a pipe 26, which leads to a source of liquid under pressure (not shown). The valve 120 is provided with a stem 27, composed of two parts, 28 and 29, the part 28 being secured to a sleeve 30 and the part 29 to a sleeve 31, the two sleeves being held in the expanded relation by a spring 32. A push button 33, movable in the lower part 34 of the housing, is connected with each valve stem part 29, and carries a projection 35 in whose path is a switch 36, for closing the circuit through the motor 9 by way of conductors 37 and 38. When it is desired to operate the valve 120 for controlling the passage of liquid through any branch pipe, the corresponding push button

33 is moved inwardly and its initial movement closes the switch 36 and starts the motor. At the same time the fruit will be applied to the head 14 and the operation of 5 removing the pulp and juices from the fruit will be quickly accomplished and after or during this operation the valve stem 27 will be further actuated by the push button and sufficiently to unseat the valve 120, whereby 10 the liquid is allowed to enter the chamber 21, the valve 120 being unseated by rearward pressure on the head 14 to allow the liquid to pass through a small spout 39, whereby it is brought into contact with the head and 15 the fruit, the pulp and juices being removed from the head and carried downwardly through an opening 46 into a glass 41, or other suitable receptacle.

During the initial pressure of the push 20 button 33, the part 28 of the stem will be held against movement by the pressure of the liquid on the valve 120 through the pipe 26, which it is assumed, as heretofore stated, is in communication with a source of liquid 25 under suitable pressure for the purpose. However, after the initial movement of the push button which has closed the electrical circuit and put the motor in operation, the further movement of the button will bring 30 the inner extremity of the sleeve 31 into contact with the rear extremity of the sleeve 30, whereby the latter will then be actuated to open the valve 120 through the medium of the stem member 28.

35 From the foregoing description, the use and operation of my improved drink-dispensing apparatus will be readily understood.

In the first instance the push button 33 40 will be actuated sufficiently to close the electrical circuit through the motor, and the fruit will be applied to the head 14 a sufficient length of time to remove or loosen the pulp and juices, and after or during 45 this operation, the push button will be further actuated and the liquid from the proper pipe 22, 23 or 24, allowed to enter the chamber 21 and pass thence through the spout 39 into contact with the head, and thence 50 through the opening 46 into the glass. Release of pressure upon button 33 will allow spring 32 to move stem 29 to break the circuit to the motor; and release of pressure on head 14 will allow spring 119 through 55 stem 19 to restore the head to original position and at the same time close valve 120.

I claim:

1. In drink-dispensing apparatus, the combination of a head, slidably and rotatably mounted, a source of liquid, a valve for controlling the supply of liquid, and an operative connection between the valve and the head, whereby the valve is operated by the head during its sliding movement.

65 2. In drink-dispensing apparatus, the

combination of a rotary shaft, a head mounted to rotate with the shaft, endwise movable and spring-held in a predetermined position, a source of liquid supply, a conduit leading therefrom to the vicinity 70 of the head, a valve normally closing said conduit, and an operative connection between the head and the valve, whereby the latter is operated by the endwise movement of the head.

75 3. The combination of a rotatable shaft, a head mounted to rotate with the shaft, endwise movable and spring-held in a predetermined position, a liquid supply conduit having its outlet in the vicinity of the 80 head, a valve for controlling the passage of liquid through said conduit, and an operative connection between the valve and the head, to operate the valve as the head is moved in the endwise direction.

85 4. The combination of a rotatable shaft, a head mounted to rotate with the shaft, endwise movable thereon and spring-held in a predetermined position on the shaft, a main liquid supply conduit having its outlet 90 in the vicinity of the head, a plurality of branch conduits communicating with the said main conduit, a normally closed valve for controlling the passage of liquid through the main conduit, an operative connection between the said valve and the head, whereby, as the head is moved in the endwise direction on the shaft and against its spring, the valve is opened, a valve normally closing each branch pipe against the passage of liquid, and means for opening any one of said last named valves.

95 5. The combination of a rotary head, a main conduit having an outlet opening in the vicinity of the head automatically controlled by the rotary head, branch conduits, communicating with the main conduit, valves for controlling the passage of liquid through the respective branch conduits, and means for operating said valves.

100 6. The combination of a motor having a rotary shaft, a head mounted to rotate with the shaft, a number of conduits for delivering liquid to the vicinity of the head, a valve for controlling the passage of liquid through each of said conduits, a motor switch for each valve, and means connected with each valve for operating the switch to close the motor circuit and subsequently open the valve by continuing the movement 110 of said means in a given direction.

115 7. The combination of a rotary head, a conduit having an outlet opening in the vicinity of the head, and a valve automatically operated through the rotary head for controlling the passage of liquid through said conduit, and means for operating said valve.

120 8. The combination of a rotatable shaft, a head mounted to rotate with the shaft, endwise movable and spring-held in a pre- 130

- determined position, a main liquid-supply conduit having its outlet in the vicinity of the head, a branch conduit communicating with the said main conduit, a normally closed valve for controlling the passage of liquid through the main conduit, an operative connection between the said valve and the head, whereby, as the head is moved in the endwise direction and against its spring, 5 the valve is opened, a valve normally closing the branch pipe against the passage of liquid, and means for opening said last named valve.
9. The combination of a rotary head with a motor for positively driving the head, a 15 conduit having an outlet opening in the vicinity of the head, and a valve automatically operated through the rotary head for controlling the passage of liquid through said conduit. 20

In testimony whereof I affix my signature.
CHARLES C. GATES.
